ATTORNEY

UNITED STATES PATENT OFFICE.

WILLIAM R. WINSSELL, OF KANSAS CITY, MISSOURI, ASSIGNOR TO HEAT-KING OIL BURNER COMPANY, INC., OF KANSAS CITY, MISSOURI, A CORPORATION OF MISSOURI.

OIL BURNER.

Application filed June 5, 1925. Serial No. 35,090.

This invention relates to oil burners and the primary object thereof is to provide a simple form of oil burner which will insure a perfect intermixing of the air or 5 oxygen content with the hydrocarbon content of the fuel mixture, to thereby provide, as nearly as practical, perfect combustion of the fuel so as to eliminate liability of soot, smoke and carbonaceous deposits on and 10 about the burner.

Another object of the invention is to provide a fire bowl or nozzle from which the flame or products of combustion will flare out and over a side zone so as to provide the 15 maximum heating effect and thereby quickly raise the temperature of the surrounding air.

It is also the purpose of my invention to provide means whereby the amount of fuel delivered to the burner may be regulated 20 and to this end I have provided means for controlling the flow of the hydrocarbon content of the fuel mixture and means for controlling the flow of air which contains the necessary oxygen to support combustion.

Structurally I have improved the invention by providing a removable oil cup or receptacle hung from the top of the tubular member and removably secured therein, the cup being so located that oil may be flowed 25 into it across the axis of the tubular member. The oil cup has an upstanding strip connecting the cup to a spider-like head with a central opening in it to receive the pipe which supplies the liquid to the tubular member. The cup can be easily removed for 30 inspection or repairs.

The burner per se really consists of but three parts, the tubular member with the broad flat flame bowl, the rotatable damper, 40 and the cup, so it will be apparent that the cost of manufacturing the assembly will be comparatively slight.

The novel details of construction of the invention will be clearly understood by reference to the following description in connection with the accompanying drawings, in which

Fig. 1 is a perspective view of a burner constructed in accordance with my invention.

Fig. 2 is a perspective view of the oil cup. 50

Fig. 3 is a longitudinal, sectional view through the burner, and

Fig. 4 is a plan view.

The main shell or casing 1 is tubular and is open at both ends. At one end is a 55 broad flat shallow flame bowl 2 with an upwardly curved bottom 3 to provide easy stream lines for the combusted fuel. At the other end of the tube is an upstanding bracket portion 4, also integral with the tube 60 and to it is pivoted the damper 5, secured to the bracket 4 by a stove bolt 6. The damper has openings 7 which may coincide with the opening at the end of the tube 1 above the bracket 4. When the damper is thrown around in one direction, the opening 7 will coincide with the bracket 4 so that the damper will be closed. When it is moved in an opposite direction, the openings 7 may 65 more or less overlap the edge of the bracket 70 4 and according to the extent that they do overlap, will determine the effective port area through which air may pass.

In the top of the tube 1 is an opening 8 to receive a spider 9 having a depending strip 75 10 which carries a cup 11 having serrated outer edges, as at 12. The spider has a central hole 13 to receive the end 14 of a supply pipe 15, connected to a source of supply and provided with a valve 16 so that 80 the effective port area of the pipe 15 can be controlled.

The burner will first be primed by opening the valve 16 and allowing oil to flow into the cup 11 and if necessary, over the serrated edge 12. Then it will be ignited and after the burner becomes hot, the oil will immediately vaporize and continue to be vaporized as long as the burner is in operation. 85

The broad flat shallow bowl with the curved bottom will deliver the flame over a wide expanse so that the surrounding air may be quickly and efficiently heated. The amount of fuel used may be governed, of 90

course, by controlling the valve 16 and the damper 5 because one will bear a definite relation with respect to the other.

What I claim and desire to secure by Letters-Patent is:

An oil burner comprising a tubular member having an air intake at one end and a vapor outlet at the other, the tubular member being provided with an opening in its

upper wall, a spider receivable in the opening having a depending strip, a cup carried by the strip suspended above the bottom of the tubular member, and a pipe for discharging through an opening in the spider into the cup. ¹⁰

In testimony whereof I affix my signature.

WILLIAM R. WINSELL.
